(57) **CLAIM**

The ornamental design for a combined faucet handle and hub, as shown and described.

DESCRIPTION

FIG. 1 is a perspective view of the new design for a combined faucet handle and hub;

FIG. 2 is a left elevational view of the new design for a combined faucet handle and hub, the right elevational view being a mirror image;

FIG. 3 is a top plan view of the new design for a combined faucet handle and hub;

FIG. 4 is a bottom plan view of the new design for a combined faucet handle and hub; and,

FIG. 5 is a front elevational view of the new design for a combined faucet handle and hub, the rear elevational view being a mirror image.

The broken lines in FIG. 4 are for illustrative purposes only and form no part of the claimed design.
